UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONDUCTOR-GRIP.

1,012,971.

Specification of Letters Patent.

Patented Dec. 26, 1911.

Application filed January 30, 1908, Serial No. 413,433. Renewed November 8, 1911. Serial No. 659,250.

To all whom it may concern:

Be it known that I, REUBEN B. BENJAMIN, a citizen of the United States, residing at Chicago, in the county of Cook and State of Illinois, have invented new and useful Improvements in Electrical Conductor-Grips, of which the following is a full, clear, concise, and exact description, reference being had to the accompanying drawing, forming

10 a part of this specification.

My invention relates to electrical devices such as incandescent lamp sockets, attachment plugs, current taps and the like and pertains more particularly to improved 15 means for gripping the electrical conductors connected therewith.

In electrical devices of the class above mentioned, the conductors connected therewith are often subjected to strains which 20 tend to loosen them from the binding terminals to which they are secured, as, for instance, where they form the means for suspending the electrical device. As it is unsafe, under these conditions, to rely upon the 25 connection of the conductors with the electrical binding posts, it becomes desirable to provide auxiliary means for securing firm mechanical attachment.

It has become quite common to knot or 30 twist the conductors inside the device to prevent withdrawal of the same through the opening provided therefor, thus relieving the electrical connection of any excessive 35 strains, but this method has interfered with attempts to secure a compact construction and a good appearance for the electrical device.

It is the object of my invention to provide 40 a conductor grip which will not add unnecessary bulk to the structure in which it is employed, which will be of simple construction, and which will admit of the ready and convenient release of the conductors when it is desired to disconnect the same from the 45 binding posts of the device.

In the accompanying drawings, Figure 1 illustrates, in elevation and partial section, an attachment plug embodying the features of my invention; Fig. 2 illustrates in elevation and partial section, a current tap device embodying the features of my invention; Fig. 3 is a sectional view taken on the line 3—3 of Fig. 2, looking in the direction indicated by

the arrows; Fig. 4 is a partial sectional view taken on the line 4—4 of Fig. 2, looking in 55 the direction indicated by the arrows; Fig. 5 illustrates, in elevation and partial section, an incandescent electric lamp receptacle embodying the features of my invention, and more particularly, a slight modification 60 therein; and Fig. 6 is a plan view of the device shown in Fig. 5, parts being removed to reveal the hidden construction.

Referring to Fig. 1, I have illustrated an attachment plug having an insulating base 65 10, one end of which is surrounded by the shoulder flange 11 of the longitudinally extending threaded sleeve 12. A threaded contact shell 13 surrounds the insulating base 10 and is provided with a portion 14 of decreased diameter which engages over the shoulder 15 of the threaded sleeve 12. A ring 16 of insulating material is secured to the threaded shell 12 to facilitate its manipulation and a cap 17, preferably of insulating material, has threaded engagement with the sleeve 12 and encounters the insulating ring 16 to retain the same in place as illustrated in the drawings. This construction as just described, admits of the free rotation of the threaded shell 13 upon the insulating base 10 and eliminates the necessity of twisting the electrical conductors 18, leading from the binding terminals carried by the base 10, when the attachment plug is 80 75 85 screwed into a socket fixture.

It is apparent that the electrical conductors 18, 18 may be frequently subjected to severe strains and it is desirable therefore to provide gripping means to protect the electrical connections. The mere attachment of the conductor wires to the electrical binding posts cannot be relied upon to meet abnormal strains, and if no auxiliary gripping means were provided, breaks and short circuits would frequently occur. My invention is directed particularly toward the provision of means for securing this additional safe guard. Broadly the principal feature of my invention consists in a member interposed between the conductors tending to spread the same apart and a second member disposed immediately proximate thereto tending to draw the conductors together. The combination of these oppositely acting 100 95 105 tendencies serve to securely clamp the con-

ductors in place, and I embody this principle in a simple and convenient construction and a compact arrangement of the clamping members and the parts with which they may necessarily be associated. While the broad feature of my invention would consist in any member interposed between the conductors, I have herein shown a disk of particular form which is provided with oppositely disposed notches to accommodate the conductor wires. In Fig. 1, I have illustrated this disk at 19 and its particular form is best illustrated in Fig. 4 which will be hereinafter more particularly referred to. This disk is provided with the oppositely disposed notches 20, 20 which accommodate, respectively the conducting wires 18, 18, and the periphery of the disk is such that it may be disposed within the threaded sleeve 12. The disk 19 rests upon the insulating base 10 and the conductors 18, 18, lead from the base and pass through the notches 20, 20 on opposite sides of the interposed portion 21. The cap 17, which has threaded engagement with the sleeve 12, is provided with the central opening 22 through which the conductor wires 18, 18 may pass, this opening being of such size, relatively to the interposed portion 21 of the disk 19, that, when the cap 17 is screwed down firmly into the sleeve 12, the conductors 18, 18 are drawn together immediately next the disk 19 so that they are forced into an offset, as at 23. The conductors are thus firmly clamped between the cap 17 and the disk 19, and the inwardly extending portions of the conductors are relieved of any strain applied to the outwardly extending portions thereof.

In Figs. 2, 3, and 4 I have illustrated a current tap comprising a plug and a lamp receptacle and means for making connections with an auxiliary circuit. The plug portion, similarly to the attachment plug, has the insulating base 10 upon which is rotatably mounted the threaded contact shell 13 with its insulating ring 16. The insulating base 10 carries the socket base 24, and upon this base are mounted the shell contact and the center contact which connect with the terminals of an incandescent lamp inserted in the socket. Binding terminals 25, 25 are carried by the base 24 and are suitably connected with the contact members of the socket and the plug. The conductors of the auxiliary circuit are adapted to be connected to these binding posts. The base 24 is surrounded by the casing 26 held in place by the screws 26^a, and a suitable insulating lining 27 is interposed between the base and the casing. The casing is provided with a side opening 28 to accommodate the conductors of the auxiliary circuit, and a laterally extending threaded sleeve 29, having a shoulder 30, leads from this opening and is flanged over at 31 to secure its rigid attachment upon the casing. The disk 19 which has heretofore been described is disposed in this threaded sleeve 29 against the shoulder 30 and is held in place against rotation by means of the punched protuberances 32, 32 extending inwardly from the sleeve 29 and engaging in corresponding notches 33, 33 in the disk. The conductors 18, 18 leading from the binding terminals 25, 25 are led through the notches 20, 20 in the disk 19 on opposite sides of the central spreading portion 21. A clamping member 34 has threaded engagement with the sleeve 29 and similarly to the clamping member 16, is provided with a central opening 35, and when this clamping member is screwed down into the sleeve 29, the conductors 18, 18 will be held rigidly in place, as has been described with reference to Fig. 1. The clamping member 34 is preferably constructed of insulating material so that it may form an insulating bushing for the sleeve.

In Figs. 5 and 6 I have illustrated the broad feature of my invention applied to a lamp receptacle, such as are commonly suspended by the conductors themselves, and I have therein shown a slight modification within the scope of my invention. The base 36 of the receptacle carries the lamp contacts and the binding terminals and is surrounded by a casing 37 having the insulating lining 37^a. This casing has the cap 38 removably secured thereto and this cap is provided with an opening 39 for the exit of the conductors 18, 18 leading from the binding terminals on the base. A screw-threaded sleeve 40 extends longitudinally from this opening. In this modification, instead of providing an auxiliary disk as in the hereinbefore described embodiment of my invention, I provide as a member for separating the conductors, a boss 41 integral with the base 36 and properly disposed relative to the sleeve 40 as illustrated in Figs. 5 and 6. The conductors 18, 18 are led from the terminals out of the device on opposite sides of this boss and extend out through the opening 39 and the threaded sleeve 40. The insulating bushing or clamping member 34 has threaded engagement with the sleeve 40 and, when screwed down in place, will clamp the conductor wires 18, 18 securely in position as has been before described with reference to the other forms of my invention.

I claim as new and desire to secure by Letters Patent,

1. In an electrical device having binding terminals adapted to have lead conductors connected thereto, a spreading member, means for clamping the conductors against said spreading member, said spreading member and said clamping means being arranged to distort the conductors when the latter are clamped between them, and means

for immovably supporting said spreading member at the side thereof opposite to said clamping means.

2. In an electrical device having an opening for the entrance of conductors, a threaded sleeve at said opening, a shoulder in said sleeve, a spreading member disposed against said shoulder by which the conductors may pass, and a clamping ring threaded in said sleeve through which the conductors may pass.

3. In an electrical device having an opening for the entrance of conductors, a threaded sleeve at said opening, a shoulder in said sleeve, a spreading member disposed against said shoulder by which the conductors may pass, and a clamping member threaded in said sleeve and having an opening for the passage of the conductors, said opening being of a diameter less than the width of that

portion of the spreading member between said conductors plus the thickness of the conductors.

4. In an electrical device having an opening for the entrance of conductors, a threaded sleeve at said opening, a shoulder in said sleeve, a disk disposed against said shoulder and having notches therein to accommodate the conductors, and a clamping member threaded in said sleeve and having an opening therethrough for the passage of the conductors for clamping the conductors against said disk.

In witness whereof, I have hereunto subscribed my name in the presence of two witnesses.

REUBEN B. BENJAMIN.
